(57) **CLAIM**

The ornamental design for: fishing rod holster, as shown and described.

DESCRIPTION

FIG. 1 is a top plan view of a fishing rod holster showing my new design;

FIG. 2 is a right side elevational view thereof;

FIG. 3 is a front elevational view thereof;

FIG. 4 is a left side elevational view thereof;

FIG. 5 is a bottom plan view thereof;

FIG. 6 is a rear elevational view thereof; and,

FIG. 7 is a perspective view showing the invention in use, the broken line showing of environment being for illustrative purposes only and forming no part of the claimed design.
